CORSET

Hans Lebbenberg, London, England, assignor of part interest to Trubenised (Great Britain) Limited, London, England, a British company

Application July 8, 1949, Serial No. 103,659

Claims priority, application Great Britain July 23, 1948

8 Claims. (Cl. 2—36)

1

This invention relates to corsets and particularly although not exclusively to corsets in which so called bones are disposed substantially vertically in the front portion of the garment to afford support for the stomach and diaphragm of the wearer. The term "bones" is here and throughout the specification and the appended claims to be understood as including stiffening strips of metal, Celluloid and other hard and resilient materials and not as limited to the strips of whalebone to which the term was originally applied.

In such corsets, as at present constructed, there is a tendency for the upper edge portion of the corset to become permanently folded or rolled forwardly over the upper ends of the bones, even though the latter are disposed with their ends as close as possible to the edge of the corset. Another disadvantage of such corsets is that the upper ends of the bones press against the flesh of the wearer when she bends forward, causing considerable discomfort, particularly when the corset extends substantially above the natural waist line, as required by current fashion.

According to one feature of the present invention these disadvantages are avoided by disposing the bones with their upper ends spaced at some little distance downwardly from the upper edge of the corset and securing in the front portion of the corset stiffening fabric which extends downwardly from the upper edge of the corset alongside the upper parts of the bones. Preferably the stiffening fabric extends also across the tops of the bones, a convenient arrangement being to accommodate the upper part of each bone in a correspondingly shaped slot extending upwardly from the lower edge of a piece of stiffening fabric which is secured with its upper edge level with the upper edge of the corset. The corset is thus stiffened right up to the edge sufficiently to prevent the usual folding or rolling over and at the same time the wearer is afforded protection against injury by the ends of the bones.

The stiffening and protecting strips may be formed by a single thickness of felt or other suitable material, but they are most conveniently made from a so-called fused fabric assembly, consisting of three or more superimposed plies of fabric adhesively united together by means of strands of potentially adhesive material contained in one or more of the plies.

Such fused fabric stiffening strips may also be employed with advantage in corsets which are not provided with bones and the invention includes a corset having a front panel comprising inner and outer fabric layers and a plurality of fused fabric stiffening members extending down-

2

wardly from the upper edge of the panel and secured by stitching between said fabric layers.

A corset constructed in accordance with the invention is shown by way of example in the accompanying drawing, in which Figure 1 is a perspective view of the corset, Figure 2 is a perspective view on an enlarged scale of a portion of the front panel of the corset with parts broken away and removed to show the construction thereof and Figure 3 is a sectional view on a still further enlarged scale, taken on the line III—III of Figure 2.

The corset illustrated comprises a front panel designated in general as 1, a pair of side panels 15 2 and a back panel 3, a sliding clasp fastener 4 forming a detachable connection between the upper parts of one side edge of the front panel and of the adjacent side edge of one of the side panels. An elastic gusset 5 is provided in the centre of 20 the lower edge of the front panel and four stocking suspenders 6 are attached to the lower edge of the corset.

The front panel comprises an outer fabric layer 11 and an inner fabric layer 12. Between these 25 fabric layers there are disposed three bones 13 which extend downwardly from points a short distance below the upper edge of the corset. For each of these bones there is provided a piece of stiffening fabric 14, cut from a three-ply fused fabric assembly, which is secured by stitching to the outer face of the inner fabric layer 12, the upper edges of the members 14 being on a level with and conforming to the shape of the upper edge of the front panel. Each of the members 30 14 is formed with a slot 15 extending from the lower edge thereof towards the upper edge, this slot being shaped and dimensioned to accommodate snugly the upper part of one of the bones 13. The bones, which are provided with fabric cover 35 strips 16 and 17, are laid into the slots in the parts 14 and secured in position by stitching their cover strips to the inner fabric layer 12.

The size and shape of the stiffening and protecting members 14 may be varied within fairly wide limits, but in the particular corset illustrated, each of these members was cut from an initially rectangular piece of material measuring some two inches in height and one and a half inches in width. In the completed corset, the upper part of each of the bones 13 is bordered 45 on three sides by a stiffening strip about half an inch in width. The side edges of the members 14 lie fairly closely adjacent one another, so that together they form an almost continuous band of stiffening along the upper edge of the corset 50 which effectively prevents the latter from rolling over downwardly, without impairing the circumferential flexibility of the corset.

It will be understood that the invention is not limited to the particular arrangement and mode of construction described and illustrated, these being given by way of illustrative example only.

I claim:

1. A corset or like garment comprising a fabric body portion for encircling the body, a plurality of bones secured to the front of said body portion and extending downwardly from points spaced below the upper edge of said body portion, and a plurality of fabric stiffeners more flexible than said bones also secured to the front of said body portion, each of said stiffeners having an upper edge level with and conforming to the shape of the upper edge of said body portion and each of said stiffeners including a central part extending downwardly from said upper edge to a point immediately above the upper end of one of said bones and two side parts extending downwardly from said upper edge and in non-overlapping relationship alongside of and closely adjacent to the upper part of said one bone.

2. In a corset or like garment, a front panel comprising inner and outer layers of fabric secured together, a plurality of stiffening members composed of multiple plies of fabric fused together disposed between said layers of fabric and secured with their upper edges level with the upper edges of said layers, each of said stiffening members being formed with a recess extending from the lower edge of said member towards the upper edge thereof, and an equal plurality of bones also disposed between and secured to said fabric layers, said bones respectively having upper parts snugly fitted in said recesses, respectively, of said stiffening members.

3. In a corset or like garment, a front panel comprising inner and outer layers of fabric secured together by stitching, a plurality of stiffening members composed of multiple fused plies of fabric disposed between said layers of fabric and secured by stitching in closely adjacent side by side relationship with their upper edges level with the upper edges of said layers, each of said stiffening members being formed with a recess extending from the lower edge of said member towards the upper edge thereof, and an equal plurality of bones also disposed between and secured to said fabric layers, said bones respectively having upper parts snugly fitted in said recesses, respectively, of said stiffening members.

4. A corset or like garment having a front portion comprising inner and outer layers of fabric secured together with their upper edges in register, a plurality of bones disposed in spaced substantially parallel relationship between said layers and extending downwardly from points below the upper edges of said layers, an equal plurality of flat U-shaped stiffeners disposed between said layers and composed of multiple plies of fabric adhesively united together, each of said stiffeners closely surrounding the upper portion of one of said bones and having an upper edge level with and conforming to the shape of the upper edges of said layers, said stiffeners having their side edges lying closely adjacent one another.

5. In a garment having an upper edge and an elongated bone mounted on said garment with an end portion of the bone located adjacent to but spaced from the upper edge of the garment, a substantially U-shaped stiffener consisting of a plurality of fused fabric plies located closely about the end portion of the bone with opposite

legs of said stiffener on opposite sides of said bone and with a portion of said stiffener connecting said opposite legs thereof extending between the bone and the upper edge of the garment, whereby the end portion of the bone is prevented from projecting into the body of the wearer and whereby the upper portion of the garment cannot be rolled over by the wearer.

6. In a garment having an upper and a lower edge, in combination, stiffening means secured to the garment, and having an outer edge located along the upper edge of the garment, said stiffening means extending from the upper edge of the garment toward the lower edge thereof and being formed with a recess extending inwardly from an edge distant from said outer edge thereof; a bone having an end portion thereof located in said recess of said stiffening means; and a fabric pocket enclosing said bone, being partly located in said recess and being secured to said stiffening means, whereby said stiffening means forms an extension of the bone which prevents the upper part of the garment from being rolled over and prevents the end portion of the bone from projecting from its position in the garment.

7. A corset or like garment comprising a fabric body portion for encircling the body, a plurality of bones secured to the front of said body portion, being spaced from each other and extending in substantially parallel relation downwardly from points located adjacent and spaced below the upper edge of said fabric body portion, and a plurality of fabric stiffeners of lesser stiffness than said bones also secured to the front of said body portion, said stiffeners each having an upper edge level with and conforming to the shape of the upper edge of said body portion and said stiffeners each having a lower portion extending downwardly from said upper edge of said body portion in non-overlapping relationship alongside of and closely adjacent to the upper part of one of said bones, said lower portions of said stiffeners being located between said bones, and said stiffeners each being composed of multiple fused plies of fabric.

8. A corset or like garment having a front portion comprising inner and outer layers of fabric secured together with their upper edges in register, a plurality of bones disposed in spaced substantially parallel relationship between said layers and extending downwardly from points below said upper edges of said layers, and a plurality of stiffening members composed of multiple fused plies of fabric and secured by stitching with their upper edges level with the upper edges of said layers, said stiffening members having lower parts lying in non-overlapping relationship alongside of and between the upper parts of said bones.

HANS LOBBENBERG.
